(57) **CLAIM**

The ornamental design for an ice cream mold, as shown and described.

DESCRIPTION

FIG. 1 is a top, rear, right side perspective view of an ice cream mold showing my new design;

FIG. 2 is a bottom, front, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, rear, right side perspective view of the ice cream mold, shown exploded and in a condition for use for clarity of disclosure;

FIG. 10 is a bottom, rear, right side perspective view of the ice cream mold, shown exploded and in a condition for use for clarity of disclosure; and,

FIG. 11 is a bottom, front, left side perspective view of the ice cream mold, shown exploded and in a condition for use for clarity of disclosure.

The broken lines shown in the drawings depict portions of the ice cream mold that form no part of the claimed design.
